AIR PUMP

Filed Feb. 3, 1930

Fig. 1.

INVENTOR
Samuel Silvers,
BY
G. S. Kennedy,
ATTORNEY

UNITED STATES PATENT OFFICE

SAMUEL SILVERS, OF WATERLOO, IOWA

AIR PUMP

Application filed February 3, 1930. Serial No. 425,620.

My invention relates to improvements in air pumps and an object of my improvement is to furnish a device of this class adapted for removing deposits or obstructions from 5 ducts, lavatories, toilet seats or their traps by the propulsion of charges of compressed air thereinto.

Another object of my improvements is to combine in this device a compression-pump 10 for supplying air under a desired pressure in a chamber having a delivery nozzle with a valve controllable manually from without, the pump having manually controllable operating means also without the chamber and 15 arranged relative to the means for controlling said valve, that the valve may be opened conveniently or with the same hand that is used to operate the pump, when the desired pressure of air in the chamber has been attained.

Another object is to supply for said chamber a reversibly mounted delivery device of elastic material and having opposite parts shaped differently for use with variously 25 sized and shaped conduit openings, and employing removable fastening means for securing said device in either of its said reversed positions and against displacement.

Another object of my improvements is to 30 combine with a discharge valve-seat of said chamber a valve therefor having an entrant guide terminal to prevent unseating of the valve when opened, and said valve having a handled stem traversing the chamber outwardly, manually operable for seating or unseating said valve.

Another object is to supply an air-pump 40 in combination with said chamber and to compress and deliver air under compression thereinto by manual operation without the chamber, said pump being supplied with a resiliently controlled delivery terminal valve for cooperating with a piston, whereby the reciprocatory pumping elements of the pump are governed suitably in any working positions while compressing and delivering compressed air to the chamber.

My invention is not restricted to the precise construction or arrangement of parts 50 shown herein, nor the various details, as the

same may be modified variously without departing from the scope of this invention or from the protection of the appended claims.

I have accomplished the above objects by the means which are hereinafter described and claimed, and which are illustrated in the accompanying drawings, in which Fig. 1 is a central vertical longitudinal section of my improved air pump, with some parts in elevation. Fig. 2 is a vertical transverse section 60 of the cupped discharge nozzle as mounted on the discharge conduit in a reversed or inverted position to permit a differently shaped optional terminal thereon to be used in certain applications of the device. Fig. 3 is a 65 top plan of the compression chamber of the device with associated operating devices.

The numeral 1 denotes a hollow cylindrical air-compression chamber having closed upper and lower heads 3 and 2 respectively. 70 The lower head 2 has an aperture with inwardly bent interiorly threaded rim 4 to seat a threaded end of a depending discharge conduit 5, a nut 6 seated on the conduit securing it in place. The lower portion of said conduit is exteriorly threaded at 21 to seat first a stop-nut 22 and at the lower end a securing nut 23.

The numeral 17 denotes an elastic rubber discharge nozzle or cup of conical hollow shape with a depending and thinner concentric rim 18. The upper part 19 of said cup is conically diminished at 19 for a purpose to be disclosed. The threaded part 21 of the conduit 5 traverses and fits the central bore 20 of the upper part 19 which is thus clamped securely on the conduit 5 by the lower nut 23. As shown in Fig. 2, when the nut 23 is removed, the cup 17 may be inverted, and after the nut 23 has been mounted on the threaded part 21 of the conduit against the upper nut 22 the part 21 therebelow may be seated in the hollow 20, the lower end of the conduit thus being spaced a short distance 85 above the lower end of said hollow, which thus provides an elastic termination for the coned part 19. The cup 17 is used to sealingly and elastically conformably fit around the mouth of rather large diameter of a con- 90 95 100

duit or hollow body to be cleaned, such as that of a toilet seat above a trap or the like, and the coned diminished opposite part 19 because of its coned shape may be inserted in a smaller opening as that of a pipe or the like to yieldingly fit and seal the same, in either case the elastic conformability thereof preventing escape of air at the joint.

The upper end of the conduit 5 extends a short distance within the chamber 1 and thus provides a valve-seat therein. The upper head 3 has an inwardly rimmed and interiorly threaded apertured seat 7 for a threaded sleeve 8 projecting upwardly having securing and locknuts 9 and 10 thereon, and a valve-stem 12 is slidably fitted in said sleeve 8, and has a cross-handle 11 at its upper end, and a stop annulus fixed at 13 thereon within the chamber to limit upward movement of the stem. The lower termination of the stem 12 is threaded to receive first a conical cap-nut 14 which extends more or less at all times into the valve-seat end of said conduit 5 to prevent displacement of an apertured rubber coned valve 15 secured on the stem 12 by an upper nut 16, said valve 15 fitting and closing said seat when the handle 11 is manually pushed downwardly. The handle is also used manually to seat or especially unseat the relief-valve 15 when the air is sufficiently compressed in the chamber 1.

The upper head 3 is also apertured with an inwardly turned interiorly threaded rim 24 to seat the threaded part of a hollow sleeve 25 nut 25 which is traversed by the cylinder 26 of a manually operable air-compression pump having a removable centrally apertured cap 27 threaded thereon. The aperture 28 of said cap is of larger diameter than a piston-stem 30 traversing it, and having a top cross-handle 31. The aperture thus serves as an air-inlet for said cylinder. The stem 30 has side projections 29 to serve as stops to limit downward movement of the stem. A downwardly opening rigid cup 39 on the lower end of said stem gives support to an inclosing cup 40 of flexible leather or other material fitting the inner wall of the cylinder yieldingly, the cup 39 being spaced to allow of play of the rim of the cup 40, whereby when on its upward or suction stroke the flexible rim collapses inwardly to permit air to pass the piston downwardly, and when the piston is pushed down the air is compressed under the cap 40 to cause its rim to hug the cylinder and preventing return leakage of air. The coiled spring 41 on the stem 26 serves as an elastic stop at the upper end of the piston stroke.

The lower end of the cylinder 26 is open with an inturned conical rim 32 to fit upon a diminished part of an apertured rubber valve 33 mounted on the short stem 34 of a disk 36 apertured at 35 and slidably fitting the inner wall of the cylinder above a spacing sleeve

on said stem. A cap-nut 37 on the lower end of the stem secures the valve on the stem. A coiled compression spring within the cylinder is engaged with the end rim part 32 and with said disk 36.

In operation either end part 18 or 19 of the rubber cup 17 may be applied around the mouth or orifice of a device to be cleaned of adherent substances, as the case may be, then the operator, by reciprocating the handled stem 31 of the pump, the valve 15 having been previously manually closed, pumps air into the chamber 1 to a suitable degree of compression, which may vary from about 30 to 80 pounds per square inch, the degree of compression being indicated on the scale 44 seen through a window 43 of a pressure gage 42 in communication with the top of the chamber, and by an index finger 45 movable over the scale. The hand which holds the pump handle 31 can then conveniently also grasp the cross-handle 11 on the relief-valve stem 12 to lift the valve from its seat, discharging the compressed air in a single charge from the chamber 1 through the member 17 into the device to be cleaned, the concentrated force of the air charge being usually sufficient to detach and discharge any adherent deposits, but if necessary the operation may be repeated.

All of the operating and connected elements of this device are so removably secured together, as to remain in place without loosening or detachment during such operations.

Having described my invention, what I claim as new, and desire to secure by Letters Patent, is:

1. In a valve-controlled air-compression chamber, an air-pump mounted removably in said chamber having a manually operable flexibly cupped piston and an air-inlet permitting air to pass the piston on its suction stroke only, said pump comprising a cylinder containing said piston and having an open inner end with a valve-seat, an apertured slide-member fitting the cylinder and having a rigid connection with a valve mounted thereon to control said valve-seat delivery, the valve being without the cylinder, a resilient compression spring engaged between said valve-seat and said slide-member to normally retain the valve against its seat, the other end of said cylinder projecting without the chamber and having an apertured end which provides said air-inlet, and said piston having a handled stem projecting loosely through said inlet.

2. In a valve-controlled air-compression chamber, an air-pump cylinder mounted to depend within said chamber, having its inner end shaped with a valve-seat and its outer end apertured centrally as an air-inlet, a handled stem slideable loosely in said air-inlet and having on its inner end within the cylinder a flexible cupped piston with an interior rigid

cup whereby air may pass the piston only on its suction stroke, an elastic coned valve fitting said valve-seat from without and having a short stem extending into the cylinder with 5 an apertured head thereon fitting the cylinder slidably, a coiled compression spring around said stem and engaged between the lower seat part of the cylinder and said head, and a coiled compression spring mounted 10 loosely on said piston-stem to serve as an elastic stop against the upper cylinder head.

3. In an air-pump, the combination of a cylinder having an apertured head, a piston-rod traversing loosely said aperture from 15 without, a piston secured on said piston-rod composed of a rigid backing member spaced from the inner wall of the cylinder and a flexible member collapsible thereagainst to permit passage of air past the piston on its suction stroke only, and a resiliently controlled 20 aperture valve device in the delivery end of the cylinder separably engageable with the piston to be actuated thereby in one direction to discharge air at the latter part of the suction stroke of the piston.

In testimony whereof I affix my signature.
SAMUEL SILVERS.
